UNITED STATES PATENT OFFICE.

ISAAC B. SHUTE, OF CAMBRIDGE, MASSACHUSETTS.

CARPET-SWEEPER.

SPECIFICATION forming part of Letters Patent No. 269,127, dated December 12, 1882.

Application filed February 17, 1882. (No model.)

To all whom it may concern:

Be it known that I, ISAAC B. SHUTE, of Cambridge, in the State of Massachusetts, have invented Improvements in Carpet-Sweepers, of 5 which the following is a specification.

The object of my invention is to insure a constant contact of the requisite pressure between the brush-cylinder and the friction-wheels, which imparts rotary motion thereto; 10 and the invention will, in connection with the accompanying drawings, be hereinafter fully described, and specifically defined in the appended claim.

Figure 1 is a perspective view of a sweeper 15 having my invention embodied therein. Fig. 2 is an end elevation, taken as viewed from the right in Fig. 1, and with a portion of the end of the case broken away to show the interior arrangement of parts. Figs. 3 and 4 are side 20 elevations of the adjustable brush-supporting brackets, which are secured to the ends of the case.

A represents the case, which is of well-known construction, and B is the usual cover thereto. 25 A bail, a, provided with the usual tongue or handle, b, is shown as secured to case A in a well-known manner.

The brush-cylinder c (shown without the bristles in Fig. 1 and with them in Fig. 2) is 30 provided with the usual arbor or journals, n, upon which it rotates, which motion is imparted to it by the action of friction-wheels e, which bear upon the carpet, and also peripherally en-

gage said cylinder c, as shown. Said journals n are supported in the brackets d, which are 35 formed with an open slot, h, at the bottom of which is formed a seat, k, for said journals, which are secured therein by springs i, whose studs l are formed to extend into said seats and to bear against the journals, as shown, 40 thereby constantly pressing cylinder c into contact with the friction-wheels e to insure the desired action thereof. Said brackets d are also formed with slots j, which receive the screws by which they are secured to ends f, and which 45 also allow the requisite vertical adjustment of the brush when it is seated in the brackets, as described. The springs i are secured to the brackets in either of the methods shown, and so that they will exert the requisite force 50 against the brush-journals for the described purpose.

I claim as my invention—

In a carpet-sweeper, and in combination with brush-cylinder c and friction-wheels e thereof, 55 the brackets d, slotted and provided with the arbor-recess k, as shown, and spring i, secured to the bracket and provided with a stud, l, to engage arbor n and press the same into said recess, whereby cylinder c is held in contact 60 with wheels e, substantially as specified.

ISAAC B. SHUTE.
